US00D677746S

(12) **United States Design Patent**
Baudhuin et al.

(10) **Patent No.:** **US D677,746 S**
(45) **Date of Patent:** **** Mar. 12, 2013**

(54) **EXERCISE BICYCLE**

(75) Inventors: **John R. Baudhuin**, Venice, CA (US);
John C. Cook, Ventura, CA (US)

(73) Assignee: **Mad Dogg Athletics, Inc.**, Venice, CA
(US)

(**) Term: **14 Years**

(21) Appl. No.: **29/374,086**

(22) Filed: **Jun. 30, 2011**

(51) LOC (9) Cl. **21-02**

(52) U.S. Cl. **D21/667**

(58) Field of Classification Search D21/662-670,
D21/694, 697; 482/51-52, 57-65; 280/261,
280/266, 282, 284, 288.1, 288.3, 304.4, 835;
D12/111

See application file for complete search history.

(57) **CLAIM**

The ornamental design for an exercise bicycle, as shown and described.

DESCRIPTION

FIG. 1 is a right side view of an embodiment of an exercise bicycle.

FIG. 2 is a right side view of an embodiment of an exercise bicycle.

FIG. 3 is a rear view of an embodiment of an exercise bicycle.

FIG. 4 is a front view of an embodiment of an exercise bicycle.

FIG. 5 is a bottom view of an embodiment of an exercise bicycle.

FIG. 6 is a top view of an embodiment of an exercise bicycle.

FIG. 7 is a left rear perspective view of an embodiment of an exercise bicycle.

FIG. 8 is a right side view of an alternate embodiment of an exercise bicycle.

FIG. 9 is a left side view of an alternate embodiment of an exercise bicycle.

FIG. 10 is a rear view of an alternate embodiment of an exercise bicycle.

FIG. 11 is a front view of an alternate embodiment of an exercise bicycle.

FIG. 12 is a bottom view of an alternate embodiment of an exercise bicycle.

FIG. 13 is a top view of an alternate embodiment of an exercise bicycle; and,

FIG. 14 is a left rear perspective view of an alternate embodiment of an exercise bicycle.

The broken lines illustrate portions of the exercise bicycle which form no part of the claimed design.

1 Claim, 14 Drawing Sheets
